(57) **CLAIM**

The ornamental design for the adhesive sheet for substrate, as shown and described.

DESCRIPTION

FIG. 1 is a perspective view of the front, top and right side of the adhesive sheet for substrate showing our new design; FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof; and,

FIG. 8 is a perspective view showing usage status thereof. The broken line showing of the adhesive sheet for substrate is included for the purpose of illustrating portions of the adhesive sheet for substrate and forms no part of the claimed design.

1 Claim, 4 Drawing Sheets
